UNITED STATES PATENT OFFICE.

LOUIS SCHMIDT, OF HANOVER, GERMANY, ASSIGNOR TO SIEMENS & HALSKE A. G., OF BERLIN, GERMANY, A CORPORATION OF GERMANY.

HIGH-TENSION RECTIFIER FOR ALTERNATING CURRENTS.

1,070,542.

Specification of Letters Patent. Patented Aug. 19, 1913.

Application filed March 26, 1912. Serial No. 686,434.

To all whom it may concern:

Be it known that I, LOUIS SCHMIDT, a citizen of the Empire of Germany, and residing at Hanover, Germany, have invented 5 certain new and useful Improvements in High-Tension Rectifiers for Alternating Currents, of which the following is a specification.

This invention relates to rotary high tension rectifiers and has for its primary object 10 to provide an improved construction, whereby a device of this character can be simply and economically constructed and adapted to operate with a maximum degree of efficiency.

15 A further object is to provide for a more compact arrangement of parts without in any manner lessening its serviceability.

Among other objects, my invention contemplates the elimination of certain objectionable features inherent in present well known machines of this character.

One illustrative embodiment of my invention is diagrammatically represented by way of example in the accompanying drawing, 25 wherein:—

Figure 1 is a perspective view of a rectifier arranged for a four-pole machine, and Fig. 2 is a diagram of connections showing the paths of the currents at a given instant.

30 Heretofore it has been customary to construct rotary high tension rectifiers by arranging stationary contact-pieces in three planes for the purpose of obtaining the necessary insulation. The main drawback to 35 this construction was due to the excessive length of the apparatus which is undesirable by reason of inconvenience in handling and reduction in efficiency due to losses. It has been proposed to obviate these defects by 40 arranging the fixed contacts in two fixed planes and in alinement along the rotating axis. This construction is objectionable however by reason of the necessity of passing conductors through the axle which was 45 made hollow for that purpose. With this arrangement it is difficult to prevent the circuit from becoming grounded. To obviate these difficulties, the axle was made entirely of insulating material resulting in an undesirable 50 lack of rigidity in the apparatus. On the other hand, machines have been put into service with insulating plates or layers disposed between adjacent contacts to prevent flashovers. This construction is more or less 55 objectionable by reason of the considerable

increase in the cost of manufacture, it being necessary to make the insulating plates very thick and of high grade material. To obviate all of these drawbacks while retaining all the advantageous features of the other 60 machines, constitutes the main general object of the present invention.

Referring firstly to Fig. 1, the steel axle *a* of the rectifier is coupled to a motor, not shown, driven by current from the circuit 65 supplying the current to be rectified, and carries two pairs, *b* and *c*, of intersecting arms *b*₁, *b*₂, and *c*₁, *c*₂ made of insulating material and inclosing acute angles. The outer ends of each pair of these arms are securely connected by the electrically conducting, segmental bridge-pieces *d*₁, *d*₂, *d*₃ and *d*₄, which are suitably insulated from the axle. Between the bridge-pieces *d*₁, *d*₃ and between the bridge-pieces *d*₂, *d*₄, which are respectively located on the same side of the axle, are mounted the two conductors *e*₁ and *e*₂, respectively, which are parallel to the axle and form the connections between their respective pairs of bridge-pieces. In or near 70 each of the two planes containing these bridge-pieces are mounted four stationary contact-pieces *f*₁, *f*₂; *f*₁', *f*₂'; *f*₃, *f*₃' and *f*₄, *f*₄' arranged in such manner that, when the axle rotates, they are either directly contacted by 75 the bridge-pieces or are as close as possible thereto so that spark-gaps are formed across which the current can pass. By means of this construction, it is possible to utilize almost the entire half wave-length of the alternating current, whereas in known rectifiers comprising four curved contact-pieces located in one plane it is possible to utilize only a comparatively small portion of the wave-length, otherwise a discharge would 80 take place between the contact-pieces. Moreover these known rectifiers have the defect that they comprise a bored axle traversed by the movable conductors. At each end of 85 the rectifier the fixed contacts are connected to one another in pairs, the pair at one end being connected to the source of supply, and that on the other end to the apparatus requiring the rectified current. The connections at the one end are displaced 90° relatively to the corresponding connections at the other end of the rectifier. In the illustrative embodiment the secondary winding of a transformer is used as the source of alternating-current supply, to whose terminals 100 95 105 110

the fixed contact-pieces f_3, f'_3 and f_4, f'_4 are connected in pairs. The apparatus requiring the rectified current is in this case, a Röntgen tube R whose terminals are connected to the fixed contact-pieces f_1, f_2 and f'_1, f'_2 .

Referring now to Fig 2, the arrows shown in full lines indicate the direction of the currents when the rectifier is in the position shown in Fig. 1, while the dotted arrows show the direction of the currents after the axle has rotated through an angle of 90°.

It is to be understood that the conductors arranged parallel to the axle may be formed as points opposite curved stationary contacts without departing from the scope of my invention.

I claim:—

1. A high potential rectifier comprising two pairs of terminal members, the elements of each pair being angularly displaced 90 degrees with respect to the elements of the other pair, in combination with two pairs of rotary sectors, insulated from each other, the elements of which are spaced apart but electrically connected.

2. In a high potential rectifier, the combination with two pairs of conductors insulated from each other and suitably mounted

to revolve about an axis, the elements of each pair being spaced along said axis, but electrically connected, of fixed contacts arranged in pairs adjacent the paths of revolution of the revoluble conductors, the elements of each pair of fixed contacts being angularly displaced 90 degrees with respect to each other.

3. In a device of the character described, the combination with a source of alternating currents having two terminals, a pair of fixed contacts connected up to each terminal, an instrumentality for utilizing rectified alternating currents, said instrumentality being provided with two terminals, a pair of contacts connected to each terminal of said instrumentality, and two pairs of rotary sectors insulated from each other and the elements of which are spaced apart but electrically connected, the elements of each pair of contacts being angularly displaced 90 degrees with respect to each other.

In testimony whereof, I have signed my name to this specification in the presence of two witnesses.

LOUIS SCHMIDT.
